Primary Examiner — Ian Simmons*Assistant Examiner* — Rhea Shields*(74) Attorney, Agent, or Firm* — King & Spalding LLP(57) **CLAIM**

The ornamental design for a multi-port USB device, as shown and described.

DESCRIPTION

FIG. 1 is a front side perspective view of a first embodiment of a multi-port USB device, showing my new design.

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is a front side perspective view of a second embodiment of a multi-port USB device, showing my new design.

FIG. 9 is a front elevation view thereof;

FIG. 10 is a back elevation view thereof;

FIG. 11 is a right-side elevation view thereof;

FIG. 12 is a left-side elevation view thereof;

FIG. 13 is a top plan view thereof; and,

FIG. 14 is a bottom plan view thereof.

The broken lines shown represent unclaimed subject matter and form no part of the claimed design.
